UNITED STATES PATENT OFFICE.

JAMES KEITH FRANCE, OF SHAMROCK, SASKATCHEWAN, CANADA.

WAGON-BOX END GATE.

Application filed January 7, 1926. Serial No. 79,789.

My present invention relates to improvements in a wagon box end gate appertaining more particularly to a locking device therefor.

5 An object of this recent invention is to provide a locking device of this kind that cannot work loose with the jolting of the wagon but, on the other hand, the fastening lever automatically tightens when 10 moved into operative position and is there releasably but securely held.

15 A further object of the provision of such an end gate and fastening means is that the gate is positively prevented from working loose or sagging.

20 To the accomplishment of these and related objects the invention resides in the construction, combination and arrangement of parts as shall be hereinafter more fully described, illustrated in the accompanying drawings and pointed out in the claims hereunto appended.

25 The invention can be best described and most readily understood when reference is had to the drawings of the preferred embodiment of the invention and in which like characters indicate like parts throughout the several views.

30 Fig. 1 is an elevation of my improved end gate.

Fig. 2 is a plan thereof;

35 Figs. 3 and 4 are vertical sections through the end gate showing the fastening means with locking lever retained by the spring keeper and moved into and out of locking position respectively.

40 In a grain wagon box especially there is need of having a leak proof end gate for an inestimable loss of grain occurs annually from loose or ineffective end closures.

45 To overcome this unnecessary waste my invention comprises an end gate formed of two sections hinged together with a tongue piece applied rigidly to one of these sections and adapted to overlap and extend longitudinally of the other section on which is mounted a fastener to lock the tongue. The usual pair of vertical guide strips are provided near the back end and on the inside 50 of the side walls of the wagon box between which the ends of my improved gate are designed to engage.

55 Reference is now had particularly to the attached drawings wherein is shown a wagon 5 with a box 6 of conventional design. At the rear end of the inside of each of the

side walls of the box are provided a spaced pair of upright guides 7 between which the end gate 8 engages.

60 The gate is shown as comprising two sections 9 and 10 hinged together on the inside as at 11. A tongue 12 is mounted rigidly on the former gate section 9 and extends over the hinged end thereof to overlie and extend longitudinally of the outer face of 65 the latter end gate section 10.

65 The feature of this invention is the locking means, the preferred embodiment of which is here disclosed as including a spring keeper 14 and a fixed or rigid stop 70 member 15, these arranged in vertical alignment with the former uppermost. These parts in the order noted are mounted on the tongue 12 near the free end thereof by nuts and bolts 16 or other suitable means.

75 Though the stop piece 15 comprises but a single piece of sheet metal, it may comprise spring steel of the like doubled on itself to form an abutment with the upper or stop surface 17 horizontal and the lower side 80

18 inclined as a brace with the ends of both top and bottom sides of such abutment bent to laterally engage the tongue 12 to which it is secured by the bolt 16 through the straight end of the lower part. The spring 85

keeper 14 will preferably be formed of a back plate 19, through which the fastening bolt 16 passes, and the spring lock or keeper element 20, substantially L-shaped. The in-turned upper end 21 of this spring element 90

is tucked under the top edge of the back plate 19 and there fastened to it. It then continues downwardly therefrom and angularly to the said back plate, that is applied laterally to the tongue, bends at an acute 95 angle to make the stop or retaining wall 22

that confronts the upper horizontal surface of stop 15, being spaced from and parallel thereto. This inturned end 22 extends into a seat or cavity 23 cut through the tongue 12 100 and into the gate member 10 and, as it has been found best in practice to form the stop member 15 and back plate 19 unitary, entrance to the cavity 23 will be through this member.

105 The fastening bar 24 is pivoted at 25, to the gate member 10, parallel with the pocket between the bottom of the spring finger 14 and the stop 15. The end 26 of this locking bar 24 is offset laterally from the end gate 110 to give clearance from the tongue and to enable the lever to better ride up on the

spring finger 14 to depress the same when passing into locking position and to permit of the operator getting a grip thereon to pivot the same either into or out of position.

As will be seen on reference to Fig. 3, the space between the horizontal inturned end of the spring finger 14 and the top stop surface of the stop member 15 is ample to accommodate the lever arm 24 that in locked position is normally held therein. It is further obvious that to release such lock arm the spring finger 14 must be depressed, this being done manually.

From the foregoing description taken in connection with the accompanying drawings, it will be manifest that a wagon box end gate is provided which will fulfill all the necessary requirements of such a device, but as many changes could be made in the above description and many apparently widely different embodiments of my invention constructed within the scope of the appended claims without departing from the spirit or scope thereof, it is intended that all matters contained in the said accompanying specification and drawings shall be interpreted as illustrative and not in a limited sense.

What I claim as new and desire to secure by Letters Patent is:—

1. In a wagon box end gate formed of two sections hinged together with a tongue rigidly applied to one of said sections, designed to overlie and extend longitudinally of the second of said sections, said tongue having a cavity therein near the free end, a lock therefor comprising a stop member formed of a plate applied rigidly to said tongue, the same having a stop projecting laterally from the said tongue; said plate having perforations therethrough centrally of the ends thereof, an L-shaped spring

member, the top end of which is bent on itself and retained by said plate, being tucked under the top thereof, and inclining outwardly therefrom to a position in line with said perforation where it bends acutely to enter said cavity through said perforation, and a fastening lever pivotally mounted on the second of said gate sections and designed, when in locked position, to be releasably held between the confronting sides of said spring member and said stop member.

2. A wagon box end gate formed of two sections hinged together with a tongue rigidly applied to one of said sections and designed to overlie and extend longitudinally of the second of said sections; a spring keeper carried on said tongue and having outwardly projecting portions of substantially V-shaped form with its top surface extending in a horizontal plane and its lower side inclined; said spring keeper, said tongue and the second mentioned gate section having registering openings immediately above said outwardly projecting portions of the spring keeper; a spring lock having one end secured at the upper end of said spring keeper while its main portion is curved outwardly and downwardly and its lower end bent at an angle for operating in said registering openings; and a locking bar pivoted on said second mentioned gate section and adapted to ride over the main portion of said spring lock and press the latter inwardly until released by the locking bar sliding off the main portion thereof and seating automatically in its operative position between the said horizontal upper face of the outwardly extended portion of the spring keeper and the free turned lower end of said spring lock.

In testimony whereof I hereunto affix my signature.

JAMES KEITH FRANCE.
